CANDLE BASE AND ASSEMBLY

Marcia C. Hamblet, Kew Gardens, N. Y.

Application March 29, 1941, Serial No. 385,808

7 Claims.

(Cl. 67—23)

This invention relates to a candle base and assembly. More particularly the invention relates to a candle assembly of economical and light construction that is adapted to float in water and maintain a burning candle in an upright position.

In order to obtain the desired economy and lightness in weight, I use preferably sheet material to form the structural elements of the base. I form the selected sheet material into desired shape defining a buoyancy-giving space adapted to receive a candle, coat the shaped material with wax or the like so as to form a continuous waterproof coating over the material, and balance the weight of the base in desired manner around the candle-receiving space. There is thus provided a water-tight chamber extending from the bottom of the candle base to a height somewhat above the level to which the candle base will be submerged when carrying the candle and resting in water.

The invention comprises the herein described candle base and assembly with the candle. More specifically, the invention comprises a candle base constructed largely of waterproof material such as waterproofed paper or the like and including means for holding a candle in upright position within the base.

As the sheet material for use in constructing the core of the base, paper crepe is particularly unsatisfactory. This material is relatively inexpensive and adapted to be shaped without tearing. It is adapted, also, on being dipped into wax at a temperature slightly above the melting point of the wax, to become impregnated with the wax and to retain over the surface a layer or film of wax which gives a waterproof exterior to the paper crepe.

Other sheet materials that may be used in place of the crepe paper are fabrics such as crepe de Chine or Cellophane. These other materials, however, are relatively expensive and less readily worked than the crepe paper. The paper is, therefore, the preferred material. Papier-mâché, a plastic plaster of Paris, or other suitable material may be used to form the base, as by molding or hand shaping.

The wax used in making the candles for the assemblies of the present invention is of conventional type and the candles are preferably of standard diameters.

Since the bases are more expensive than the candles which they are to receive, it is desirable that the base should be reusable a large number of times, by simply inserting a fresh candle after

a former one has been burned away. For such reusable bases, I use a coating of waterproofing material, as, for example, wax of melting point substantially above that of the wax in the candle, say 10° or more above. Thus, when the wax of the candle melts in the range of 120 to 126° F., the wax of the exterior of the candle base should have a minimum melting point of about 130 to 140° F.

In place of the wax as waterproofing material on the members of paper or like which are present in the base, there may be used other suitable waterproof materials as, for example, an incombustible lacquer, a varnish, or a plastic. This said material may be applied in any convenient way, as by dipping or spraying in solution in a volatile solvent. Thus, there may be used to advantage a resin lacquer such as one of the glyptal or vinylite resin lacquers.

Suitably, a lower portion of the base extends downwardly from an upwardly flaring portion of the base, the whole having a low center of gravity that is preferably below the line of submergence of the base when resting in water with a candle in position in the assembly. The whole should be balanced. That is, the center of gravity of the article should be approximately in an imaginary line passing vertically through the center of the candle when the candle is seated in the base.

The invention will be illustrated in more detail by description in connection with the drawing to which reference is made.

Fig. 1 is a perspective view of a preferred form of candle base, with a candle seated in the base.

Fig. 2 is a sectional view of line 2—2 of Fig. 1.

Fig. 3 is a sectional view of a modified form of assembly, with the candle base floating in water.

Fig. 4 is a vertical sectional view of a modification in which a molded material without reinforcement is used in the construction of the base.

Fig. 5 is a side view partly in section of a modification in which the candle base takes the general form of a boat.

Fig. 6 is a sectional view on a somewhat enlarged scale of the assembly of core and waterproofing material used in constructing the base of Figs. 1, 2, 3, and 5.

Fig. 7 is a view of a modification of the core and waterproofing material.

There are shown an assembly of candle 9 and a base of lower portion terminating in members 10 resembling the foliage of a flower and an upper portion including petal-like members 11

fashioned and assembled in the manner of the corolla of a flower, the parts 10 and 11 being coated with waterproofing material and defining a water-tight space adapted to receive the candle. Suitably the candle is of short length and terminates within the said space.

In the form shown in Fig. 2, means for seating the candle 12 in the space defined by members 10 and 11 include a short tube 13 of cardboard, plastic, aluminum, or other light-weight material. Suitably, the sheet or sheets of which the members 11 are composed is gathered together around the tube during the construction and held in position as by a band 14 of rubber, thread, fine wire, or the like.

In the form shown in Fig. 3, the tube for holding the candle is omitted. In constructing this type of assembly, a standard candle 15 is provided and the parts 11 are gathered therearound and held in position by the element 25 similar to element 14 that has been described. The partially constructed assembly is then dipped into wax, excess wax drained away, and the wax solidified. The part 10 is then applied as will be described later.

In the form shown in Fig. 4, molded material 16 without core material, is used in construction of the base of desired ornamental pattern defining a space 17 adapted to receive a candle.

In Fig. 5 there is shown a modification in the form of a candle assembly including a boat 18 as the base, the ring element 19 for receiving the candle, a member or weight 20 of high specific gravity, say, a piece of metal such as iron, copper, lead, or the like. The weight is disposed in the lower part of the candle assembly. It stabilizes the floating and keeps the candle assembly in an upright position when placed on water. In the case of the boat-shaped base, the weight may raise the prow above the water line as shown.

In order to make the construction of the base as ornamental, economical, and light in weight as consistent with durability, there is used preferably a material 21 or 22, suitably paper crepe, a woven fabric such as crepe de Chine, Cellophane, or the like as core material within the members constituting the base. Crepe paper is preferred because of its relatively low cost and the readiness with which it may be shaped into the flower or other ornamental pattern without tearing.

The relation of the waterproofing material 23 to the sheet materials 21 is shown in various figures, and particularly in Fig. 6. The construction shown in Fig. 7 using a woven fabric core 22, may be substituted for the material of Fig. 6 in the bases shown in Figs. 1, 2, 3, and 5.

In general, the method includes first the shaping of sheet material, such as that commonly used in the making of artificial flowers or other ornamental objects, by technique that is usual in making such objects, the shaping providing a space to receive a candle of standard diameter. After the ornamental pattern is formed, it is held in desired shape temporarily, as by elements 14 or 25, and then coated with waterproofing material as by dipping or spraying. Suitably the waterproofing material is wax and the wax is applied by dipping the shaped core material into the wax at a temperature a few degrees above the melting point of the wax and draining away excess of wax. Other waterproofing materials are applied either in melted condition or in solution in a volatile solvent, as, for example, in a lacquer.

When different colors are desired, say, for the foliage 10 and corolla 11, then separate dippings are required. In such a case the corolla of paper crepe or the like is assembled around the candle 5 or the tube 13 and then is dipped so as to give a continuous coating of waterproof material over the parts constituting the corolla. This dipping may be in rose-colored wax, for example. Then core material such as paper crepe, which is to 10 constitute the interior of the foliage 10, is scalloped on one side of the strip and the strip is dipped one or more times in wax of desired color, say green. Before the final application of wax hardens completely, the strip is wrapped 15 around the lower portion of the corolla assembly and folded on itself at the bottom of the assembly, to give a water tight structure, as illustrated more or less diagrammatically at 24. The lower part is then again dipped in the waterproofing material, to make certain that the lower part of the assembly is completely water-tight. This coating is made rather thick so as to give to the whole a low center of gravity which is 20 below the point of submergence of the base when 25 holding a candle and resting in water. In this final dipping, care is taken that the wax of color used for the foliage does not strike any part of the assembly that is differently colored, as, for example, the rose colored petal-like members.

30 In making the base or shape shown in Fig. 5, a boat of crepe paper or other sheet material of the kind described is formed in any suitable manner and provided with the upstanding member 19 held initially to the boat by adhesive (not shown) and then secured in position finally by dipping the boat and ring in wax of desired color. A weight 20 is inserted in position.

In making a molded product such as shown in Fig. 4, there is used any suitable plastic. Thus, 40 there may be used a urea-aldehyde, a phenol-aldehyde, or a casein plastic, shaping being made to pattern desired in accordance with technique that is conventional for shaping the selected plastic. The bases formed from these plastics 45 as well as those made from the waterproofed crepe paper are shape-retaining when floating in water, that is, they do not sag or become distorted in water. Also, their upper portions flare outwardly and, being thus spaced from the 50 candle, do not melt as the candle burns. The bases may be reused a number of times, fresh candles being inserted in used bases as described elsewhere herein.

Bases constructed as described are relatively 55 light in weight, economical in amount of wax or other waterproof material used, and may be made in highly ornamental patterns. Furthermore, the use of flexible core material in the leaf or petal-like members adapts the base to be light in weight in its upper portions so as to give a low center of gravity to the whole. All the bases should be balanced if the bases are to be floating 60 when in use.

The candle may be either replaceable or an 65 integral part of the base. If the candle is replaceable, a standard candle of color to suit the user may be inserted into position and a new candle of the same diameter introduced into the base after one candle has been burned away. In some embodiments of the invention, however, the candle is introduced into the base at the place of fabrication and may be held in position temporarily by a small amount of wax which extends as an integral mass from the upper surface 70 of the candle to the tube 13, or, in case the 75

tube is omitted, to the portions of the corolla gathered around the candle.

While the invention has been illustrated by description in detail in connection with a floating candle base, it is to be understood that the construction, including core material such as 21 or 22 and wax or like waterproofing material constituting a continuous layer over the core, may be used in non-floating candle bases, in those cases in which the feature of floating is not desired. In other words materials of construction such as illustrated in Figs. 6 and 7 or in Fig. 4 may be used in any shape of candle base, although I have obtained unique results when the candle base is adapted to float.

The floating candle assemblies, also, may be varied in certain details. Thus a weight, such as the member 26, may be used with any shape of floating candle assembly. When the weight is to be embedded in or anchored in wax or other hardenable material, is placed in its selected position in the lower part of the assembly before the said material hardens, so that the position of the weight is established when the material sets. The weight may also be used with unbalanced designs of candle assemblies, whether or not they are to be floated when in use. This makes possible candles of a wide variety of designs that, without the added weight, would topple over or be subject to being easily upset, because of the center of gravity falling either outside or near an edge of the base.

It will be understood also that the details given are for the purpose of illustration and that variations within the spirit of the invention are intended to be included within the scope of the appended claims.

What I claim is:

1. A base adapted to receive a candle and when supporting the candle to float on water, the base comprising a lower portion, a flaring portion extending upwardly from the lower portion and defining a watertight buoyancy-giving space of width substantially greater than the diameter of the candle to be received within the base, and means for securing the lower end of the candle within the said lower portion, supporting the weight of the candle, and fixing unchangeably the level of the lower end of the candle with respect to all parts of the said base, the candle base being waterproof over its exterior surface, containing material of higher melting point than the temperature of melting of the wax of the candle, and having its center of gravity below the line to which the base when supporting a candle sinks in water, so that the base remains upright.

2. A floating candle base in the pattern of a flower including a plurality of flaring petal-like members arranged in the manner of the corolla

of the flower, waterproof leaf-like elements disposed outside the petal-like members and extending downwardly from positions above the lower parts of the said members, and means closing the spaces between the side portions of the leaf-like elements to a level above that to which the base sinks when supporting a candle and floating in water, so as to form a closed watertight lower portion of the assembly and form a buoyancy giving space above the said lower portion, a part of the said lower portion having a bottom and side walls shaped to receive the lower end of a candle and maintain the said lower end at a fixed level with respect to all parts of the base and the said buoyancy giving space being wider than the said part shaped to receive the candle so that the buoyancy giving space persists after the candle is inserted into the base.

3. A candle base as described in claim 2, the petal-like members and leaf-like elements being flexible.

4. A candle base as described in claim 1, the material of the base comprising a shaped mass of molded plastic waterproof material.

5. A base as described in claim 1 including a metal mass-adding-member of a substantially higher specific gravity than any other part of the assembly disposed in the lower part of the said base, the buoyancy-giving space causing the whole assembly to float when placed in water and the metal member stabilizing the floating and maintaining the assembly in an upright position.

6. A floating candle assembly comprising a candle and a reusable base constructed of formed shape-retaining material that does not melt at the temperature of melting of the wax of the candle and is waterproof over its exterior surface, the base including upwardly extending leaf-shaped elements that are continuously united in watertight manner at their side portions and are shaped to form a bottom for supporting the lower end of the candle and a space above the bottom for engaging and holding the side wall of the lower end of the candle at a fixed level with respect to all other parts of the assembly, the said elements flaring at their upper portions and defining around the candle a buoyancy-giving watertight space of greater width than the diameter of the candle.

7. An assembly as described in claim 6, the base being formed from paper and the paper being coated continuously over its exterior surface so as to provide waterproofing over the exterior part of the candle base, with a wax of substantially higher melting point than the wax of the candle.

MARCIA C. HAMBLET.
